UNITED STATES PATENT OFFICE.

EUGENE M. SCOVILLE, OF MILWAUKEE, WISCONSIN, ASSIGNOR OF ONE-HALF TO
FLOYD L. SWANBERG, OF PITTSBURGH, PENNSYLVANIA.

GREASE PUMP.

Application filed November 3, 1924. Serial No. 747,697.

This invention relates in general to improvements in the art of automatically transporting semi-fluid substances, and relates more specifically to improvements in the construction and operation of mechanism for positively and effectively distributing predetermined quantities of material such as grease from a common source of supply through suitable conductors to any number of points of utilization.

An object of the invention is to provide simple and efficient mechanism for pumping semi-fluid substance such as grease.

Some of the more specific objects of the invention are as follows:—

To provide a simple and compact pump of relatively large capacity which is capable of positively and continuously pumping semi-fluid such as grease.

To provide improved pumping mechanism which is adapted to distribute regulated quantities of semi-fluid from a common source to several independent points of utilization.

To provide a multi-unit pump structure in which any of the individual units may be cut into or out of operation at will, or entirely removed or restored, without interfering with the normal operation of any of the other units.

To provide an improved multi-unit pumping system which is extremely flexible in operation.

To provide means for effecting rapid and accurate variation of the capacity or rate of delivery of a semi-fluid pump or the like, and for independently controlling the operation of each of several operatively associated units.

To provide improved pump structure all parts of which are conveniently accessible and removable and similar elements of which are interchangeable.

To provide means for facilitating the construction of grease pumps and the like with the aid of drills and other ordinary machine tools.

To provide a simple and efficient visible indicator for semi-fluid pumping devices, whereby the actual condition of operation of the mechanism is discernible at all times.

To provide effective means for eliminating air pocketing in grease pumps or the like.

To provide a compound multi-unit grease

pump in which the initial compression stage is common to all of the units while each unit has its own final compression stage and resultant pressure.

To provide improved operating mechanism for a multi-unit pump or the like.

To provide improved instrumentalities for replenishing the semi-fluid or grease supply.

To provide improved gage mechanism for pump structures.

To provide various other improvements in the details of construction of pumping mechanisms, whereby the manufacture thereof is facilitated and the efficiency of operation is enhanced to a maximum.

Some of the novel features of pump structure disclosed but not specifically claimed herein, form the subject of copending applications Serial No. 567,064, filed June 9, 1922, and Serial No. 589,748, filed September 22, 1922.

A clear conception of an embodiment of the invention and of the operation of devices constructed in accordance therewith, may be had by referring to the drawings accompanying and forming a part of this specification in which like reference characters designate the same or similar parts in the various views.

taken through one of the final stage grease pumps forming part of the improved grease pumping mechanism.

Fig. 10 is a central vertical section through the casing of one of the final stage grease pumps.

Fig. 11 is a top view of the casing of one of the final stage grease pumps.

Fig. 12 is a horizontal section taken through one of the final stage grease pumps.

Fig. 13 is another horizontal section taken through one of the final stage grease pumps.

Fig. 14 is an elevation of an improved driving pawl.

Fig. 15 is an elevation of an improved locking pawl or latch.

The improved grease pumping mechanism which has been specifically illustrated, comprises in general an upper casing 7 forming a grease supply compartment having a displacement plunger 9 therein; a lower casing 6 forming a displacement compartment having a plunger 8 therein; a pump casing 2 forming a main oil supply chamber 70; an oil pump 3 supported by and located at one end of the casing 2; one or more identical final grease discharge and indicating pumps 4 supported by the casing 2 laterally adjacent to the oil pump 3; common driving mechanism for all of the pumps 3, 4; and an electric motor 5 drivingly associated with the pump driving mechanism.

As illustrated in Figs. 1 and 2, the casings 6, 7 are of different diameters and are detachable from each other for the purpose of permitting interchangeable substitution of a chamber 6 or a chamber 7 of greater or smaller capacity. As shown in Fig. 3, the 40 grease supply and the oil displacement compartments are formed in a single casing 17 and are separated by a vertically movable displacement plunger 21. The casing 17 is adapted to be substituted for the duplex casings 6, 7 of Fig. 1, if desired. The plungers 8, 9 of Fig. 1 are rigidly united by a connecting element 10 the cross-section of which is shown in Fig. 5, and are vertically movable within the casings 6, 7 respectively. The 45 space between the plungers 8, 9 is provided with a vent opening 32, and the upper ends of the casings 7, 17 are provided with removable end heads 18 of identical construction. The end heads 18 are provided with 50 grease supply openings which are normally closed by means of covers 19 held in position by means of clamps 22. Each cover 19 is provided with a check valve fitting 20 whereby grease may be forced into the grease 55 supply chamber with the aid of a grease gun such as is commonly used for lubricating automobiles, without necessity of removing the cover 19. The grease in the grease supply chamber may also be replenished 60 upon removal of the cover 19, with the aid

of a hand operated grease pump 11 such as shown in Fig. 4. This hand pump 11 has a discharge portion which snugly fits the opening in the end head 19.

The pump casing 2 having the oil supply chamber 70 formed therein is supported upon one end of a supporting plate 16 which is secured to the upper casing 7 or which may likewise be attached to the casing 17. The casing 2 is provided with a top plate 25 having elongated openings 33 therein at which the pumps 3, 4 may be applied. The front of the casing 2 is formed with a V-shaped recess within which an oil level gage 36 is located. The lower rear portion of the casing 2 is provided with a conduit 29 within which a heating or a cooling element may be inserted. The medial rear portion of the casing 2 is provided with a grease confining conduit 28 the end of which communicates with the grease compartment of the casing 7, 17 through a pipe 14, and with the upper side of which a plurality of vertical conduits communicate. Each of these vertical conduits is provided with a spring pressed ball check valve 35 which is adapted to be held away from its seat by the pronged end 60 of a plug 31, as shown in Fig. 9. When a plug 31 is in place, the corresponding valve 35 is open and grease is adapted to flow freely from the conduit 28 into the central conduit 61 of the plug. When the plug 31 is removed, the corresponding valve 35 automatically closes and prevents escape of grease from the conduit 28.

The single oil pump 3 which is located adjacent to one end of the casing 2 is shown in detail in Fig. 8 and comprises a main casing secured to the oil supply casing 2; a vertically reciprocable plunger 41 of relatively large diameter fitting a bore of the pump casing; an inlet or suction valve 49 surrounded by a strainer 46 and controlling the flow of oil from the chamber 70 to the pump displacement chamber through a conduit 48; a discharge valve 50 for controlling the delivery of oil from the pump displacement chamber to the discharge pipe 13; and a sight flow indicator 30 associated with the pump discharge line. The plunger 41 is positively elevated by means of an eccentric 42 and is held downwardly in engagement with the eccentric by means of a helical compression spring 52. The suction valve 49 is located near the bottom of the oil supply chamber 70 and is spring pressed to its seat. The discharge valve 50 which is likewise spring pressed is mounted in a removable fitting 54 to the side of which the discharge pipe 13 is also connected. The discharge pipe 13 connects directly with the lower oil chamber of the casing 6, 17 as shown in Fig. 1. The sight flow indicator 30 comprises a check valve 51 located within the fitting 54 and adjusted to permit escape of a

small quantity of the oil discharged past the valve 50 through an indicating glass and a passage 53 directly back to the chamber 70.

The grease pumps 4 of which there are any number depending upon the number of feeds desired, are identical in structure and are shown in detail in Figs. 9, 10, 11, 12 and 13. Each of the pumps 4 comprises a main casing secured to the oil supply casing 2 and the cover plate 25 at one of the openings 33; a grease displacement plunger 45 vertically reciprocable within a bore of the pump casing; an oil displacement plunger 48 vertically reciprocable in a parallel bore 10 of the pump casing; suction and discharge valves cooperable with the plungers 45, 48; and a sight flow indicator associated with the plunger 48. The casing of each grease pump 4 is detachably secured to the casing 2 by means of one of the plugs 31 and the conduit 61 of the plug 31 forms the suction passage leading to the grease pump suction valve 58 which is confined by a removable plug 69. The displacement chamber of the 20 grease plunger 45 has an ordinary ball discharge valve located in a conduit 62 located closely adjacent to the valve 58 and communicating directly with a conduit 66. The plunger 45 is provided with an annular 25 groove 59 below its upper end, the groove 59 being connected with the conduit 66 beyond the grease pump discharge valve by means of a conduit 65. The conduit 66 communicates with an annular passage 67 30 surrounding the plug 31 and communicating directly with one of the delivery lines 15. The oil displacement plunger 48 of each of the grease pumps 4 has a suction valve 56 located near the bottom of the chamber 70 35 and surrounded by a strainer 46, the valve 56 controlling the flow of indicator oil from the chamber 70 to the displacement chamber of the plunger 48 through a conduit 44. The discharge valve 57 of the indicator 40 pump plunger 48 controls the delivery of oil from the displacement chamber through the conduit 68 and the sight flow indicator, back to the chamber 70 through the conduit 63. The grease plunger 45 is rigidly secured to an actuating plate 55 while the oil plunger 48 has a relatively loose connection 55 with the plate 55. The plate 55 and the plungers 45, 48 associated therewith, are vertically movable by means of one of the eccentrics 34, and the downward movement of each plate 55 is limited by means of a stroke adjuster 40.

The pump driving mechanism comprises a horizontal driven shaft 24 supported in 60 bearings in the casing 2 and having a polygonal medial portion to which the eccentrics 42, 34 are attached. A ratchet wheel 38 secured to the end of the shaft 24 remote from the eccentric 42, has teeth which are adapted 65 to be engaged by a movable pawl 37 and by

a locking latch 39, see Figs. 8, 14 and 15. The opposite end of the shaft 24 is provided with a cranking device 27 for initially filling the distributing lines prior to starting of the pumps 3, 4. The pawl 37 is carried by an eccentric end of the driving shaft 23 and the locking device 30 is mounted on an end of the bearing for the shaft 23, the opposite end of the shaft 23 being provided with a driving sheave 12. The sheave 12 is drivingly connected to the electric motor 5 which is supported upon the end of the plate 16 opposite to the casing 2.

During normal operation of the multi-unit grease pump, one or more of the grease 80 pumps 4 may be associated with the casing 2 and with the eccentrics 34 of the driven shaft 24 as shown in Figs. 6, 7 and 9, and the oil pump 3 is associated with the eccentric 42 as shown in Fig. 8. As the shaft 23 85 is rotated continuously by the motor 5, the pawl 37 which is mounted eccentrically of the shaft 23, imparts intermittent rotary motion to the shaft 24 through the ratchet wheel 38. The locking latch 39 functions to 90 prevent reverse rotation of the shaft 24 when the pawl 37 is being retracted. The intermittently rotating driven shaft 24 reciprocates the oil pump plunger 41 which intermittently forces definite quantities of oil from 95 the oil supply chamber 70 through the pipe 13 into the oil displacement chamber in the lower portion of the casing 6, 17. The oil thus admitted to the oil displacement chamber forces the plungers 8, 9, 21 upwardly and 100 compresses the grease in the upper grease supply chamber of the casing 7, 17 and causes grease to flow under slight pressure through the pipe 14 into the confining conduit 28. Simultaneously with the operation 105 of the pump 3, the plungers 45, 48 of the grease pumps 4 are being reciprocated by means of the eccentrics 34. The reciprocating grease plungers 45 of the pumps 4 receive grease under pressure from the conduit 28 past the valves 58 and deliver the grease at a predetermined rate through the conduits 62, 66, 67 to the distributing lines 15. The reciprocating indicator plungers 48 withdraw oil from the chamber 70 past the 115 suction valves 56 and deliver the oil past the discharge valves 57 through the sight flow indicators 26 back to the chamber 70. As the oil pump plunger 41 reciprocates, a portion of the oil displaced thereby is also 120 passed through the sight flow indicator 30 and returned to the chamber 70. It will thus be noted that the pump 3 functions to effectively compress the grease in the supply chamber and that the pumps 4 simultaneously function to urge the initially compressed grease at predetermined rates through the several distributing lines 15 to the points of utilization; the sight flow indicators 26, 30, all of which utilize oil as an 125 130

indicating medium, positively indicating the condition of operation of the several pumps 3, 4 at all times.

For definite speed of the motor 5, the capacity of the oil pump 3 will obviously be constant, but the capacities of the individual grease pumps 4 may be readily varied to meet varying demands, with the aid of the stroke adjusters 40. In case air enters the displacement chamber of one of the plungers 45, the grease under pressure which fills the passage 66, conduit 65 and the annular groove 59 fills any clearance space that may exist between the plunger 45 and the bore and insures positive displacement of the air by the pump plunger.

If it is desired to replenish the grease in the supply chamber, the grease may be admitted to the casing either without removing the cover 19 by admitting the fresh grease through the fitting 20, or with the aid of the hand pump 11 upon removal of the cover 19 by releasing the clamps 22. It will be obvious that the capacity of the grease supply chamber may be readily varied by substituting a casing 7, 17 of greater or smaller capacity and that the oil displacement chamber 6 may likewise be replaced by a chamber of different capacity.

It will be observed that every element of the structure is readily accessible for inspection and removal. Any one or more of the grease pumps 4 may be removed or installed without interfering with the normal operation of the other pumps thus making it possible to deliver grease through any desired number of the distributing lines 15. Practically all of the passages and bores in the pump casings may be formed with the use of ordinary drills and jigs and all similar parts of the mechanism are of like construction and hence interchangeable. The various valves are all freely accessible and removable and spherical or ball valves are utilized wherever possible.

From the foregoing description it will be apparent that the improved pumping mechanism is of simple and compact construction and is adapted to distribute regulated quantities of grease from a common source to any number of independent points of utilization. Any of the individual units may be placed into or out of operation at will without interfering with the operation of other units, and the entire system is extremely flexible. The sight flow indicators positively indicate the condition of operation of both the oil and the grease pumps and air pocketing is effectively eliminated. The improved gage 36 is effectively protected and indicates when replenishing of the grease is necessary.

It should be understood that it is not desired to limit the invention to the exact de-

tails of construction herein shown, for obvious modifications may occur to persons skilled in the art.

It is claimed and desired to secure by Letters Patent:—

1. In combination, a pump for transporting grease, an oil pump operable simultaneously with said grease pump, and a sight flow indicator for said oil pump, the quantity of oil passing through said indicator being proportional to the quantity of grease being transported by said grease pump. 70

2. In combination, a grease pump, an oil pump, means for simultaneously operating said pumps, means for simultaneously varying the capacities of said pumps, and a sight flow indicator for said oil pump, the quantity of oil passing through said indicator being proportional to the quantity of grease being delivered by said grease pump. 80

3. In combination, an enclosed grease pump, and means for indicating the condition of operation of said pump, said means comprising a sight flow indicator and means for passing through said indicator quantities of relatively thin oil proportional to the quantities of grease delivered by said pump. 85

4. In combination, an enclosed grease pump, an oil pump having a transparent discharge conduit, common means for operating said pumps, and means for simultaneously varying the capacities of said pumps, the quantity of oil passing through said transparent conduit being proportional to the quantity of grease being delivered by 100 said grease pump. 95

5. In combination, a source of oil supply, a source of grease supply, a pump, means operable by said pump for causing oil from said first source to deliver grease from said second source, a pump for discharging a predetermined quantity of the grease delivered from said second source to a point of utilization, and means for utilizing oil from said first source to effect a visible indication of 110 the condition of operation of said grease discharge pump. 105

6. In combination, a source of oil supply, a source of grease supply, means for utilizing a portion of the oil from said oil supply source to discharge grease from said grease supply source, a plurality of distribution lines, and means for circulating other portions of the oil from said oil supply source to indicate the rate of delivery of grease 120 from said grease supply source to said lines. 115

7. In combination, an oil supply source, a grease supply source, a pump for urging a portion of the oil from said oil supply source into said grease supply source to deliver grease therefrom, a plurality of distribution lines for receiving said delivered grease, and a pump for circulating another portion of 125

the oil from said oil supply source to indicate the rate of delivery of grease from said grease supply source to each of said lines.

8. In combination, a grease supply casing, an oil supply casing supported by said grease supply casing, a plurality of pumps supported by said oil supply casing, and a driving motor for said pumps supported by said grease supply casing.

10 9. In combination, conduit means for confining grease under pressure, a plurality of pumps having suction lines associable with said conduit means, means for effecting independent removal of said pumps, and valves 15 for automatically preventing escape of grease from said conduit means upon removal of said pumps.

10. In combination, a casing forming a conduit for confining grease, a plurality of 20 pumps supported by said casing, each of said pumps having a suction line communicable with said conduit, means for effecting independent removal of said pumps from said casing, and valve means for automatically 25 preventing escape of grease from said conduit upon removal of said pumps.

11. In combination, a casing forming a conduit for confining grease, a plurality of pumps supported by said casing and each 30 having a suction line communicable with said conduit, common means associated with said casing for actuating all of said pumps, means for independently varying the capacities of said pumps, means for effecting independent removal of said pumps from said 35 casing and from said actuating means, and valve means for automatically preventing escape of grease from said conduit upon removal of said pumps.

40 12. In combination, a casing forming a displacement chamber having therein movable means which divides said chamber into segregated compartments, a pump for forcing liquid into one of said compartments to 45 positively move said movable means so as to deliver fluid from the other of said compartments, a second pump adapted to receive fluid from said other compartment, and means for varying the quantity of said 50 fluid discharged by said second pump independently of the rate of delivery of said fluid from said other compartment.

13. In combination, a casing forming a displacement chamber having therein a movable plunger which divides said chamber into segregated compartments, a pump for forcing liquid into one of said compartments to 55 positively move said plunger toward the other of said compartments, a second pump adapted to receive fluid from said other compartment, and means for varying the quantity of said fluid discharged by said second pump independently of the rate of movement of said plunger.

60 14. In combination, a casing forming a

cylindrical displacement chamber having therein a slideable plunger which divides said chamber into segregated compartments, a pump for forcing oil into one of said compartments to 65 positively slide said plunger toward the other of said compartments, a second pump adapted to receive grease from said other compartment, and means for varying the quantity of grease discharged by said second pump independently of the rate 70 of sliding of said plunger.

15. In combination, a casing forming a displacement chamber having therein movable means which divides said chamber into segregated compartments, a pump for forcing liquid into one of said compartments to 80 positively move said movable means so as to deliver fluid from the other of said compartments, a plurality of independent fluid distribution lines adapted to receive fluid 85 from said other compartment, and means for varying the quantity of said fluid delivered to each of said lines independently of the rate of delivery of said fluid from said other compartment.

16. In combination, a casing forming a displacement chamber having therein a movable plunger which divides said chamber into segregated compartments, a pump for forcing liquid into one of said compartments to 90 positively move said plunger toward the other of said compartments, a plurality of independent fluid distribution lines adapted to receive fluid from said other compartment, and means for independently varying the quantity of said fluid delivered to 95 each of said lines.

17. In combination, a casing forming a displacement chamber having therein a slideable plunger which divides said chamber into segregated compartments, a pump for forcing liquid into one of said compartments to 100 positively move said plunger toward the other of said compartments, means for varying the capacity of said pump to change the rate of travel of said plunger, a plurality of independent fluid distribution lines adapted to receive fluid from said other compartment, and means for independently varying the quantity of said fluid delivered to 105 each of said lines.

18. In combination, an oil pump, and a grease pump, said pumps being formed for interchangeable cooperation with several grease supply chambers of different capacities adapted to receive oil from said oil pump and to deliver grease to said grease pump at a definite rate.

19. In combination, an oil pump, a grease pump, and means for independently varying the capacity of each of said pumps, said pumps being formed for interchangeable cooperation with several grease supply chambers of different fixed capacities adapted to receive oil from said oil pump at a definite 120 rate.

rate and to deliver grease to said grease pump.

20. In combination, a pump casing having a bore, a piston reciprocable in said bore, and a discharge valve for controlling the final delivery of fluid from said bore by said piston, said piston having an annular recess intermediate the ends thereof normally sealed

by said bore, and said casing having a conduit formed to establish free communication 10 between said recess and the delivery side of said valve only when said plunger reaches the extreme end of its delivery stroke.

In testimony whereof, the signature of the inventor is affixed hereto.

EUGENE M. SCOVILLE.
